WINDOW SHUTTER

Alvin M. Stanfield, Jr., 8927 National Blvd.,
Los Angeles, Calif. 90013

Filed Apr. 11, 1967, Ser. No. 6,627

Term of patent 14 years

(Cl. D13—1)

FIGURE 1 is a broken front perspective view of a window shutter embodying my new design;

FIGURE 2 is a broken side elevational view of the window shutter shown in FIGURE 1;

FIGURE 3 is a fragmentary rear elevational view of the window shutter of FIGURE 1 shown with the slats closed;

FIGURE 4 is a fragmentary sectional view of the window shutter of FIGURE 1 shown with the slats closed;

FIGURE 5 is a broken rear perspective view of the window shutter shown in FIGURE 1;

FIGURE 6 is a broken top view of the window shutter shown in FIGURE 1; and

FIGURE 7 is an enlarged perspective sectional view taken along the line 7-7 of FIGURE 1.

The shutter is broken away in the several views to indicate an article of indeterminate length and width.

I claim:

The ornamental design for a window shutter, as shown and described.
